(57) **CLAIM**

The ornamental design for a connector as shown and described.

DESCRIPTION

FIG. 1 is a front elevational view of the first configuration of a connector showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a cross-sectional view thereof taken along a line 7-7 in FIG. 1;

FIG. 8 is a perspective view showing a front, top and right side thereof;

FIG. 9 is a perspective view showing a rear, bottom and left side thereof;

FIG. 10 is a perspective view showing a front, right and bottom side thereof;

FIG. 11 is a perspective view showing a rear, left and top side thereof;

FIG. 12 is a front elevational view of the second embodiment configuration of a connector showing our new design, wherein a hinge portion is in a closed state;

FIG. 13 is a rear elevational view thereof;

FIG. 14 is a right side elevational view thereof;

FIG. 15 is a left side elevational view thereof;

FIG. 16 is a top plan view thereof;

FIG. 17 is a bottom plan view thereof;

FIG. 18 is a cross-sectional view thereof taken along a line 18-18 in FIG. 12;

FIG. 19 is a perspective view showing a front, top and right side thereof;

FIG. 20 is a perspective view showing a rear, bottom and left side thereof;

FIG. 21 is a perspective view showing a front, right and bottom side thereof; and,

FIG. 22 is a perspective view showing a rear, left and top side thereof.

The broken lines in the drawings illustrate portions of the connector that form no part of the claimed design.
